UNITED STATES PATENT OFFICE.

HENRY H. LAMPERT, OF CHICAGO, ILLINOIS.

BAR-SUPPORT AND SPACER FOR CONCRETE-REINFORCEMENTS.

1,261,247.

Specification of Letters Patent. Patented Apr. 2, 1918.

Application filed November 17, 1917. Serial No. 202,439.

To all whom it may concern:

Be it known that I, HENRY H. LAMPERT, a citizen of the United States of America, and a resident of Chicago, county of Cook, 5 and State of Illinois, have invented certain new and useful Improvements in Bar-Supports and Spacers for Concrete-Reinforcements, of which the following is a specification.

10 The main objects of this invention are to provide an improved construction and arrangement of bar supporting devices for use in concrete reinforcements whereby a plurality of bar supporting and clamping means are connected together in spaced relation so that they may be quickly and conveniently placed on the falsework in properly aligned positions to receive the bars preparatory to pouring the concrete; and to 15 provide an improved manner of securing together the separately formed bar clamping means and spacing means.

An illustrative embodiment of this invention is shown in the accompanying drawings, 20 in which—

Figure 1 is a perspective view of a portion of a bar spacing and supporting device constructed in accordance with this invention, the end of a bar being shown in dotted outline on one of the clamping devices.

Fig. 2 is a fragmentary view of a modified form of spacing means.

Fig. 3 is a perspective view of a slightly modified form of bar support and a portion 35 of the spacing means.

Fig. 4 is a perspective view of one of the supporting devices with the fingers bent over a bar.

In arranging reinforcing bars for concrete 40 construction it is desirable to have the supports uniformly spaced apart transversely of the length of the bars and aligned longitudinally thereof. When the supports are separately placed on the falsework, it is necessary to mark off the position for each on the falsework and handle each one individually. This involves considerable time, and each support must be secured to the falsework or else great care exercised in order to 45 prevent them from becoming disturbed before the bars are laid. If, however, the supports are combined with a suitable spacing means whereby they are spaced apart in series or groups, they may be very quickly arranged on the falsework, and only one or two fastening means are required to secure

a plurality of clamping means in their proper positions.

To this end the construction herein shown involves the use of a spacing strip 1 and a 60 plurality of bar clamping means 2, the strip and clamping means being separately formed and afterward assembled with the clamping means located at points along the length of the strip. 65

The spacing and supporting strip 1 is in the form of a comparatively narrow strip of wrought metal, straight from end to end and provided with notches or recesses 3 extending inwardly from the opposite edges. 70 The strip is wider than the distance between the fingers on the clamping means, preferably being about equal to the distance between such fingers plus the combined width thereof. The notches 3 may be formed in 75 pairs at certain specified intervals along the strip as shown in Fig. 1, or they may be uniformly spaced apart throughout the length of the strip as indicated in Fig. 2.

Each of the bar clamping means 2 as herein illustrated is formed from sheet metal so as to provide a seat 4, depending legs 5, and upwardly disposed fingers 6. The seat 4 and depending legs 5 constitute a substantially inverted U-shaped chair, and the fingers 6 are preferably located at diagonally opposite sides thereof, although they may be located at opposite sides of one of the legs. In the construction shown in Fig. 1, the fingers 6 are bent inwardly at right angles to 85 the plane of the legs 5, whereas in the modification shown in Fig. 3, the fingers 6 are disposed in the same plane with the respective legs 5. This results in having the legs 5 disposed parallel to the longitudinal dimension of the strip 1 when a support of the type shown in Fig. 1 is used, and having the legs disposed transverse to the strip when the other type of support is used. 90

By forming the clamping means and spacing strip separate, a considerable less amount of material is required and much expense and trouble are avoided as compared with structures wherein the legs and fingers are formed from a single metal strip. 100 The parts thus formed are assembled by setting the fingers 6, disposed as shown at the left end of Fig. 1, into notches 3 on opposite sides of the strip 1 with the strip resting upon the seat 4. The fingers 6 are 105 then bent down as shown at the right of Fig. 1 so as to lock the clamping means to 110

the strip. A plurality of the clamping means are thus supported in a predetermined spaced relation along the strip, and said clamping means may be set on the 5 falsework in the desired arrangement with very little trouble and labor.

Apertures 7 are formed at points along the spacing strip 1, so that a series of the 10 supports may be nailed in position on the falsework by a few nails, or other fastening means.

The reinforcing bars 8 are placed between the fingers 6 so as to rest upon the strip 1 directly above the seats 4. The 15 fingers are then bent over the bars as shown in Fig. 4, so that they are firmly gripped to the supporting device. In case it is desired to use the supporting device at places where bars intersect, the supporting means are 20 arranged so that the lower bar extends longitudinally along the spacing strip 1 between the fingers 6. The upper bar therefore occupies relatively the same position as shown in Fig. 1, except that it rests 25 upon the lower bar.

Although but one specific embodiment of this invention has been herein shown and described, it will be understood that numerous details of the construction shown may 30 be altered or omitted without departing from the spirit of this invention as defined by the following claims.

I claim:

1. As an article of manufacture, a structure for use as a bar supporting device for concrete reinforcements, comprising a strip 35

having recesses formed therein, and bar clamping means secured thereto, said bar clamping means comprising a depending leg and upstanding fingers, said fingers engaging said recesses and coacting therewith for supporting said clamping means on said strip. 40

2. As an article of manufacture, a structure for use as a bar supporting device for 45 concrete reinforcements, comprising a strip having recesses formed therein, and bar clamping means secured thereto, said clamping means each comprising a pair of depending legs connected by a transverse part, 50 and upwardly disposed fingers located at diagonally opposite edges of said transverse part, said fingers engaging said recesses and coacting therewith for supporting said clamping means on said strip. 55

3. As an article of manufacture, a structure for use as a bar supporting device for concrete reinforcements, comprising bar clamping means each having a depending leg with upstanding fingers at opposite sides thereof, and a spacing and supporting strip for said clamping means, being of a width greater than the distance between said fingers and having notches formed in the edges thereof adapted to receive said fingers 60 whereby a plurality of said clamping means are secured to said strip at points along the length thereof. 65

Signed at Chicago this 15th day of Nov. 1917.

HENRY H. LAMPERT.
